John E. East

United States Patent Office.

WILSON NOBLE, OF NEW HAVEN, CONNECTICUT.

Letters Patent No. 92,992, dated July 27, 1869; antedated July 13, 1869.

IMPROVEMENT IN PLOWS.

The Schedule referred to in these Letters Patent and making part of the same

To all whom it may concern:

Be it known that I, WILSON NOBLE, of New Haven, in the county of New Haven, and State of Connecticut, have invented a new Improvement in Plows; and I do hereby declare the following, when taken in connection with the accompanying drawings, and the letters of reference marked thereon, to be a full, clear, and exact description of the same, and which said drawings constitute part of this specification, and represent, in

Figure 1, a perspective view, and in

Figure 2, a top view.

This invention relates, more particularly, to an improvement in subsoil-plows, the object being to reduce the friction in turning the furrow; and

The invention consists in arranging, back of the plowshare, and at an angle thereto, a wheel with a corrugated or serrated surface, so that as the earth passes over the share, it will strike the wheel, and by it be carried up and turned over, by which means the share is greatly reduced in size, and the friction, caused by the earth passing over so great a surface, is, to a great extent, removed.

In order to the clear understanding of my invention, I will fully describe the same as illustrated in the accompanying drawings.

A is the plowshare, of common construction, which extends back only sufficiently far to cut the depth and width of the furrow, as denoted in fig. 2; then in the shaft B, arranged in suitable bearings C, and lying at a point above the surface of the earth, and at an an-

gle to the course of the furrow to be plowed, I fix a wheel, D, provided, upon its surface, with corrugations a, or otherwise roughened, so as to present a shoulder to the earth as the plow passes through the furrow; therefore, when the earth, turned by the plow, strikes the wheel below the shaft, it will cause the wheel to revolve in the direction denoted by the arrow, and, with the revolving wheel, the earth will be carried up and turned over with very much less friction than if the share were continued back to produce the same result.

The bearings upon which the wheel D is arranged, should be made adjustable, so as to present the wheel at different angles.

The beam or handles are attached in the usual or any convenient manner.

I do not wish to be understood as broadly claiming the application to a plow of a wheel which is caused to revolve by the passage of the plow through the earth, as such, I am aware, is not new, as may be seen in the patent of B. C. Hoyt, September 2, 1856.

Having thus fully described my invention,

What I claim as new and useful, and desire to secure by Letters Patent, is—

The wheel D, constructed with a corrugated surface, in combination with the plowshare, substantially as and for the purpose set forth.

WILSON NOBLE.
